(57) **CLAIM**

The ornamental design for a multi function hand tool, as shown and described.

DESCRIPTION

FIG. 1 is a perspective view of a multi function hand tool embodying my new design, wherein the tools are deployed; FIG. 2 is a perspective view thereof, wherein the tools are stowed;

FIG. 3 is a front elevation view thereof, wherein the tools are stowed;

FIG. 4 is a front elevation view thereof, wherein the tools are deployed

FIG. 5 is a rear elevation view thereof, wherein the tools are stowed; and,

FIG. 6 is a left side elevation view thereof, wherein the tools are stowed, the right side view being a mirror image.
